PROJECTILE FUSE RECOVERY ASSEMBLY

Walter S. Finken, Brooklyn, N. Y., and Leonard P. Frieder, Great Neck, N. Y., assignors, by mesne assignments, to General Textile Mills, Inc., New York, N. Y., a corporation of Delaware

Application February 10, 1948, Serial No. 7,454

6 Claims. (Cl. 102—56)

1
Our invention relates to a projectile fuse recovery assembly and, more particularly, to an assembly enabling the firing of projectile fuses from large caliber rifles for the purpose of testing them and then recovering the fuses for examination and inspection.

During the last war and currently, research is proceeding with a view to developing new types of fuses for exploding projectiles such as proximity fuses and the like. It is highly desirable in connection with the development of these fuses to test them under actual firing conditions. Unfortunately however it is difficult to recover a fuse after it has been fired from a rifle in that the force of impact upon landing is such as to destroy the fuse. In event of malfunctioning of the fuse, the scrap which remains gives no clue to the reason for the failure of the fuse to function.

One object of our invention is to provide an assembly in which a new type fuse may be installed in a large caliber projectile, fired from the rifle and the fuse recovered after it has been fired and inspected to ascertain whether it functions properly or, in event of malfunctioning, the reason for its failure to function.

Another object of our invention is to provide an assembly in which the fuse to be tested is expelled from the test projectile and recovered by means of an attached parachute.

A further object of our invention is to provide an assembly for recovering fuses fired from large caliber projectiles by parachute in which means are provided for providing a time delay to permit the projectile to slow down sufficiently to enable a parachute to open and lower the fuse safely without injury thereto.

Other and further objects of our invention will appear from the following description.

In general, our invention contemplates the provision of a test projectile fitted with a fuse to be tested and containing a canister housing a parachute for lowering the fuse to the earth. After a predetermined interval of time, means are provided for expelling the canister housing the parachute and the fuse from the test projectile as a unit. After a predetermined period of time in which the canister and fuse being tested are allowed to slow down, means are provided for opening the canister to permit a parachute to be stowed. The fuse to be tested is attached to the parachute and may thus be safely recovered.

In our co-pending application Serial Number 749,228, filed May 20, 1947, now Patent No.

2,604,849, we have disclosed an illuminating projectile in which a canister containing a flare and a supporting parachute are adapted to be expelled from a projectile and, after a predetermined delay, to permit the parachute to open.

In the instant application, we have provided an improved structure, permitting a period of delay after the expulsion of a canister within which the canister may reduce its velocity before the opening of the supporting canopy, thus reducing the shock upon the canopy when it is opened and reducing the danger of fouling the shroud lines of the parachute.

We use a parachute having a hemispherical canopy and a floating hem cord such as described in United States Patent to Walter S. Finken 2,412,392 dated December 10, 1946.

In the accompanying drawings which form part of the instant specification and which are to be read in conjunction therewith and in which like reference numerals are used to indicate like parts in the various views:

Fig. 1 is the sectional view of a test projectile containing one embodiment of our invention;

Fig. 2 is a fragmentary sectional view drawn on a large scale taken on the line 2—2 of Fig. 1;

Fig. 3 is a sectional view taken on the line 3—3 of Fig. 2;

Fig. 4 is a fragmentary sectional view similar to Fig. 3 showing another construction of a delay action release mechanism forming part of our invention;

Fig. 5 is a fragmentary sectional view showing modification of the construction shown in Fig. 4;

Fig. 6 is an elevation drawn on a small scale showing the position of the parts during the expulsion of the canister and the fuse;

Fig. 7 is an elevation showing the parachute at the instant of being stowed;

Fig. 8 is a view showing the parachute canopy open and the fuse to be tested being lowered for recovery.

More particularly, referring now to the drawings, projectile 10 is provided with the usual rotating band 12. A base plug 14 is secured to the projectile body by means of shear pins 16. A liner 18 is secured within the projectile body in any appropriate manner. A pair of split sleeves 20 and 22 house a parachute 24. The lower end of sleeve 20 is provided with a flange 26 adapted to seat in a re-entrant portion formed in the body 28 of a fuse 30 to be tested. The lower end of sleeve 22 is formed with a flange 32 adapted to seat in a re-entrant portion formed in the body 28. The sleeves 20 and 22 are held in

assembled position by means of a tie member 34 which may be of any suitable material such as nylon, wire or a strap of thin metal. The securing member 34 is such that it will rupture upon the application of a suitable force, as will be pointed out hereinafter more fully. The interior side of the base plug 14 is threaded to receive the threaded portion 35 of a conventional fuse 33. The fuse 33 is well known to the art and is such that, on setback occasioned by the shock 10 of firing, a powder train will be ignited. A plurality of openings 40 are provided through which the flare of the powder train of the fuse 33 is adapted to blow into an annular space 42. The space 42 communicates with an expulsion powder charge 44 through a number of vents 46. A charge 44 of wood or the like rests upon a spacer ring 48 of wood or the like secured to the sleeve 18 in any appropriate manner. The fuse 33 is provided with adjusting rings 52 and 54 which regulate the effective length of the powder train as is well known to the art. A plate 56 is secured to the fuse 33 and carries a sleeve-separating mechanism indicated generally by the reference numeral 58.

The parachute shroud lines 60 terminate in a rat tail 62 which is secured to a swivel member 64 supported by ball bearings 66 acting against race ring 68 threadedly secured to the body 28 of the fuse 33 to be tested.

The upper end of sleeve 20 is provided with screw threads 70 adapted to engage the external threads formed on the ring 72. Similarly the upper end of sleeve 22 is provided with threads 74 adapted to engage the external threads formed upon the ring 72, which ring is positioned between the time fuse 33 and the base plug 14.

Referring now to Figs. 2 to 5 inclusive, the sleeve-separating mechanism indicated generally by the reference numeral 58 is shown in detail. It comprises a stationary body member 76 which is secured by bracket 78 and screws 80 to the plate 56. The body member is adapted to telescope within a movable member 82. The body member 76 may be considered a stationary piston and the movable member 82 acts as a movable cylinder. The cylinder 82 is closed by a plug 84 provided with a seating point 86 adapted to seat in a re-entrant portion formed in the sleeve 22 as can readily be seen by reference to Figs. 2 and 3. Threadedly secured to the body member 76 and positioned within the cylinder 82, we provide a pellet-supporting assembly 88. A member 90 supports a detonating cap 92. A firing pin 94 is releasably secured to a trigger stem 96 by means of a sleeve 98. The firing pin 94 is carried by a plate 100 which is formed integrally with a firing pin stem 102. The trigger stem 96 and firing pin stem 102 are formed with interfitting inclined surfaces 104. The ring 98 normally interlocks the firing pin stem 102 and the trigger stem 96. A ring spring 106 normally maintains the ring 98 in the position shown in Fig. 3. A firing pin spring 108 is normally under slight compression. The trigger stem 96 is provided with a cross pin 110 carried by the body member 76 as can readily be seen by reference to Fig. 2. A trigger member 112 is slidably mounted within body member 76 and the housing 114 carried thereby. The trigger member has an inclined surface 116 extending into a slot 118 formed in the upper end of the liner 18. The trigger member 112 is formed with a lug 120 adapted to contact the ring 98 when the trigger is moved to the left as viewed in Fig. 3.

The trigger is provided with an annular shoulder 122 against which the firing pin spring 108 rests. When the trigger is moved to the left, as viewed in Fig. 3, the firing pin spring 108 is first compressed against the plate 100 which is held by the firing pin stem 102 when it is locked to the trigger stem 96 by the ring 98. After the spring is compressed, the lug 120 is adapted to slide the ring 98 forwardly, thus permitting the engaging inclined surfaces 104 to cam the trigger stem 96 downwardly around the axis of the rod 110 to free the firing pin stem 104 and thus permit the firing pin 94 to fire the detonating cap 92. When the assembly moves upwardly, carrying the release mechanism with it, the trigger washer 50 is adapted to cam the trigger to the left as will be hereinafter more fully described.

When the detonator 92 is fired, it will ignite a powder pellet 124, the gases of which pass through ducts 126 past supporting spider 128 into the space 130, building up pressure tending to move the movable cylinder 82 to the left. The right hand side of the body member 76 bears against the right sleeve 20. The cylinder plug 84 bears against the left hand sleeve 22. The sleeves are held in position by the frangible member 34. The burning of the powder in pellet 124 takes a predetermined period of time. The terminal flare of pellet 124 will ignite a second pellet 132, the gases from the combustion of which pass through ducts 134 into the interior 130 of the movable piston 82 continuing to build up pressure. As the pellet 132 burns, gases will also escape through the opening 136 into the chamber 130. It will be seen that the pressure is equalized on both sides of pellets 124 and 132. The area on the right hand side of pellet rim 123 is greater than on the left hand side so that the pressure will hold the pellet on its seat. Similarly the exposed area on the right hand side of pellet rim 131 is greater than that on the left hand side of the pellet so that pellet 132 is likewise held on its seat. The detonator 92 is firmly secured in its holder 99 and is further held in position by the pressure of the firing pin spring 108. The pressure builds up by the burning of the pellets 124 and 132 to such degree that the frangible securing member 34 will be ruptured, freeing the split sleeves, as will be hereinafter more fully described.

Referring now to Fig. 4, we have shown a time delay ejector mechanism similar in principle to that shown in Figs. 2 and 3 but having a somewhat different construction. The trigger member 138 carries the cam trigger 140 and is formed with a bore in which the interfitting firing pin stem 102 and trigger stem 96 are seated. Movement of the trigger 138 to the left compresses the firing pin spring 108 and at the same time carries the bore clear of the interlocking stems so that the trigger stem 96 may pivot around pin 118 to release the firing pin. The ring 98 and the ring spring 106 are eliminated. Pellet 124 discharges its gases through ducts 126 which communicate with a manifold duct 142, emptying into the interior 130 of the movable cylinder 82. Similarly, pellet 132 discharges its gases through ducts 134 which communicate with the manifold duct 142. The action of the assembly is similar to that of the construction in Figs. 2 and 3.

Referring now to Fig. 5, we have shown a construction similar to that shown in Fig. 4. The cam trigger however has been replaced by a pivot trigger member 144 normally pivoted about a pin 146. A spring 148 biases the trigger member 144 to its full line position. The construction enables

us to assemble the projectile more readily for firing. The time ejector assembly may be inserted through the assembled split sleeves by reason of the pivoting of the trigger member 144. When it is in position adjacent the slot 118 in the liner 18, the spring will pivot it to operative position as shown.

In use, a projectile 10 is assembled with a fuse 30 to be tested as shown in Fig. 1. The time fuse 38 is set to fire after a time within which the fuse 30 to be tested should have operated. The projectile is fired from the rifle and setback initiates the action of the time fuse 38 as is well known to the art. The fuse 38 fires and the flare of the powder charge of the time fuse 38 will ignite the charge 44 positioned adjacent the base plug 14. The explosion of the charge 44 will shear the pins 16 and the assembly comprising the base plug 14, the split sleeves 20 and 22 containing the time delay ejector mechanism 48, the parachute 24 and the fuse 30 to be tested will be blown rearwardly, that is upwardly as viewed in Fig. 1, out of the shell body 10 as can readily be seen by reference to Fig. 6. The split sleeves are held in assembled position by the frangible securing member 34. The force of the explosion of the powder charge 44 is transmitted through the plug 48, through the washer 50, to the stationary liner 18, to the projectile body 10.

As the split sleeves, held in their assembled position by the securing member 34, move out of the projectile body 10 the inclined surface 116 of the trigger of the time ejector assembly will wipe past the trigger washer 50, thus camming the trigger member 112 to the left as viewed in the drawings. This action first compresses the firing pin spring 108 and then releases the interlocking cam surfaces 104 of the firing pin stem 102 and the trigger stem 96 permitting the firing pin 94 to move to the left under the impetus of the compressed firing pin spring 108. The firing pin fires the detonator 92 upon striking it, thus igniting the first time delay pellet 124. The gases discharged from the combustion of this pellet build up pressure within the space 130 within the movable cylinder 82. As the pressure builds up, the burning of the pellets will increase as an exponential function depending upon the composition of the pellet powder, the size of the pellets and the dimensions of the space into which the gases expand. After the first pellet 124 has burned, the second pellet 132 will ignite. Since this pellet burns at a greater rate, the ducts 134 for the discharge of the gases from the second pellet are of greater size than the ducts 126 which conduct the gases from the burning of the first pellet 124. A predetermined pressure is achieved within a predetermined period of time by the burning of the pellets 124 and 132. The strength of the frangible member 34 is such that it will release at a predetermined pressure. It will be observed that many variations of delay time may be easily achieved by varying the powder composition of the pellets, the dimensions of the movable cylinder 82 and the strength of the frangible securing member 34.

During the time elapsed between the ejection of the split sleeves, as shown in Fig. 6, and the time to achieve the necessary pressure to break the frangible securing member 34, the ejected assembly of the split sleeves in the parachute will have reduced their velocity to a point when the parachute may be streamed with safety. When the frangible member 34 ruptures, the split sleeves 20 and 22 will fall away, releasing the base

plug 14 and its associated time fuse 38 as well as the plate 56 carrying the time ejector assembly 58. The parachute is then free to stream as can readily be seen by reference to Fig. 7. Due to the construction of the parachute employing the spherical canopy and the floating hem cord as disclosed in the Finken Patent 2,412,392, the shock of opening will be safely borne.

As soon as the velocity of the fuse to be recovered 38 has been sufficiently reduced, the main canopy 24 will fully open and the fuse 30 will be lowered. It is to be understood of course that the entire assembly is gyrating under the influence of the twist imparted to the projectile and its contents by the rifling of the gun from which the projectile 10 was fired. The swivel connection comprising the ball bearings 66 and the raceways 64 and 68 will prevent the twisting of the shroud lines of the parachute.

In our co-pending application, Serial No. 786,861, filed November 13, 1947, now Patent No. 2,582,113, we have shown a delay assembly in which the latching means comprises a combustible or fusible connection. This connection is placed in the path of the delay pellet and is adapted upon its destruction to initiate the desired action. It will be clear to those skilled in the art that this type of release can be combined with the release assembly disclosed in the instant application. A combustible securing member may be passed through the split sleeves through opening 134 in Figure 4 so that it must be released first before the release action disclosed in the instant case will be effective.

It will be seen that we have accomplished the objects of our invention. We have provided an assembly in which new type fuses may be installed in large caliber projectiles and the fuse recovered after the firing, in order that it may be inspected to ascertain whether it has functioned properly or not and, in event of a malfunctioning, to determine the reason for its failure. We have provided an assembly in which the fuse to be tested is expelled from the test projectile and recovered by means of an attached parachute. We have provided a canister assembly in which the fuse to be tested and a canister containing the parachute is ejected from the projectile body and released after a predetermined time delay. We have provided a novel time delay ejector mechanism which is operated by the pressure of burning gases from time delay pellets.

It will be understood that certain features and sub-combinations are of utility and may be employed without reference to other features and sub-combinations. This is contemplated by and is within the scope of our claims. It is further obvious that various changes may be made in details within the scope of our claims without departing from the spirit of our invention. It is, therefore, to be understood that our invention is not to be limited to the specific details shown and described.

Having thus described our invention, what we claim is:

1. A projectile fuse recovery assembly including in combination a projectile body, a canister positioned in said body, a parachute positioned in said canister, the canister comprising a pair of sleeves surrounding the parachute, means for holding the sleeves in parachute-enclosing position, a fuse to be recovered, interengaging means formed on the sleeves and said fuse for releasably holding said fuse to the canister against longitudinal relative movement with respect there-

to, means for attaching the parachute to the fuse, an expelling charge, a time delay fuse adapted to be set into operation by the firing of the projectile from a gun for igniting said expelling charge, the expelling charge being positioned to expel the canister from the projectile body, pressure responsive time delay means carried within the canister for releasing the holding means, trigger means carried by said pressure responsive means and projecting outside of the canister and trigger actuating means mounted on the projectile body and positioned in the path of movement of the trigger means to coact with the trigger means, the construction being such that the trigger means will be actuated by the trigger actuating means during the movement of the canister out of the projectile body.

2. A projectile fuse recovery assembly as in claim 1 in which said sleeve-holding means comprises a frangible member.

3. A projectile fuse recovery assembly as in claim 1 in which said time delay means for rendering said holding means inoperative includes an ignition cap, a firing pin, a powder pellet adapted to be ignited by said ignition cap, and means responsive to the pressure of the gases of combustion of said pellet for releasing said holding means.

4. A projectile assembly including in combination a projectile body, a parachute, a canister comprising a pair of sleeves surrounding the parachute, means adapted to be supported by the parachute, interengaging means formed on said parachute supported means and said sleeves for releasably holding said supported means to the canister against longitudinal movement with respect thereto, means for holding the sleeves in a parachute-enclosing position, means for attaching said supported means to the parachute, an expelling charge, a time delay means adapted to be set into operation by the firing of the projectile from the gun for igniting said expelling charge, said expelling charge being positioned to expel the canister and the supported means from the projectile body, pressure responsive time de-

lay means carried within the canister for releasing the holding means, trigger means carried by the pressure responsive means and projecting outside the canister and trigger actuating means mounted on the projectile body and positioned in the path of movement of the trigger means during its expulsion from the projectile body by said expelling charge.

5. In a projectile fuse recovery assembly, a time delay releasing means including in combination a cylinder, a piston lodged within said cylinder for relative motion with respect thereto, a powder train, an ignition cap for igniting said powder train, a firing pin adapted to strike said ignition cap, a normally unbiased spring for actuating said firing pin, a trigger member, means actuated by the trigger member for first compressing said spring, means actuated by the trigger member for releasing said firing pin, said trigger member being provided with a cam surface and means providing communication between said powder train and said cylinder behind the piston whereby the gases of combustion are adapted to build up pressure within said cylinder to cause it to move relatively to said piston.

6. An assembly as in claim 5 in which said trigger member is mounted for pivotal movement and means for limiting the pivotal movement of said trigger member.
